UNITED STATES PATENT OFFICE.

EDWIN H. MESSITER, OF BROOKLYN, NEW YORK.

ELECTRIC CLOCK.

1,255,905.

Specification of Letters Patent. Patented Feb. 12, 1918.

Application filed December 5, 1914. Serial No. 875,576.

To all whom it may concern:

Be it known that I, EDWIN H. MESSITER, a citizen of the United States of America, and a resident of Brooklyn, Kings county, 5 and State of New York, have invented certain new and useful Improvements in Electric Clocks, of which the following is a specification, reference being had to the accompanying drawings, forming a part thereof.

10 My invention relates to clocks and other chronological instruments and has special reference to such as are maintained in operation by electricity.

I am aware that clocks of the so-called self-winding type have hitherto been known and in general use. They are provided with electric motors for keeping the main-spring under tension or for raising the weight, the spring or weight being relied upon for directly imparting driving forces to the clock mechanism. While my invention pertains to chronological devices which are driven by electricity, the device of my invention is 20 of an entirely different type from those of the prior art to which reference has just been made, since I employ and rely directly upon an electric motor for actuating the escapement mechanism.

One object of my invention is to provide 30 a simple and accurate mechanism that shall avoid the use of weights, springs and complicated gearing, and operate with very small friction losses and wear.

Another object is to provide a clock of the 35 character above indicated having a direct driving motor which shall act in the dual capacity of motor and damping device to drive and at the same time prevent too rapid movement of the escapement mechanism.

40 Another object is to provide a motor that shall consume a very small amount of energy, shall operate with great inherent regularity, and with a substantially constant or uniform torque; in fact a motor that shall 45 be particularly adapted to actuate a clock mechanism.

Other objects and advantages of my invention will be set forth hereinafter, and in order that my invention may be thoroughly 50 understood, I will now proceed to describe the same in the following specification and then point out the novel features thereof in appended claims.

Referring to the drawings:

Figure 1 is a partially sectional elevation 55 of a clock mechanism constructed in accordance with and embodying the driving motor of my invention.

A sectional elevation of the same mechanism, taken on the line 2—2 of Fig. 1, is 60 shown in Fig. 2.

Fig. 3 is a sectional view taken on the line 3—3 of Fig. 1 and illustrating the co-operation between the escapement mechanism and the lever which it actuates.

65 The same lever and the co-operating escapement mechanism is shown in another position and on a larger scale in Fig. 4.

Fig. 5 is a side elevation showing the escapement wheel in detail.

70 Fig. 6 is a view corresponding to Fig. 4, of a modified structure which also embodies my invention, and comprises a small yielding contact finger attached to the actuating lever, to effect automatic starting.

75 Fig. 7 is an end elevation of the motor armature which is of the disk-type, a portion of the rim and certain of the winding coils being broken away to show the construction in detail.

80 Fig. 8 is a view corresponding to Fig. 1, of a portion of a modified mechanism in which an impulse is imparted to the pendulum once instead of twice in each complete cycle.

85 Fig. 9 corresponds to Fig. 4 and illustrates the escapement and the actuating lever which are adapted for use with the structure of Fig. 8.

90 Fig. 10 is a detail view of a contact maker which is a part of the same mechanism.

95 Figs. 11, 12 and 13 are diagrammatic views which show the different positions of the armature disk relative to the poles of the field magnet of the motor and which clearly show the form of the pole faces.

A diagrammatic view of the circuit connections for the mechanism of Figs. 1, 2, 3 and 4 is shown in Fig. 14 while a similar view of the connections for the mechanism of Figs. 8, 9 and 10 is shown in Fig. 15.

100 Figs. 16 and 17 are respectively a sectional elevation and a detailed view of a modified motor structure which also embodies my invention.

While I have shown a Denison escapement mechanism which I now consider preferable,

my invention is not restricted to the use of any particular escapement and other well known forms may be employed. The escapement *per se* forms no part of my present 5 invention.

As hereinafter more fully pointed out, the structure shown in Figs. 8, 9 and 10 is better adapted for use in chronometers and like instruments which must operate with great 10 precision and accuracy although it possesses no extremely delicate parts nor is it otherwise restricted in its use to instruments of any particular type or service.

Referring particularly to Figs. 1 to 7 inclusive, the structure here shown constitutes one embodiment of my invention and comprises an escapement wheel 16 mounted on a shaft 17, a driving motor 18 operatively connected to the same shaft, a pendulum 19, and 20 a pendulum actuating lever or fork 20.

The shaft 17 is supported in bearing sleeves 21 and 22, which are mounted in stationary plates 23 and 24 and are insulated therefrom by bushings 25 and 26.

The motor comprises an armature 31, and a field magnet 27 which, as shown, is provided with a winding 28 and has a pair of opposed pole pieces 29—30. The armature 31 comprises a hub 32, a magnetizable disk 33 secured thereto and extending between the pole pieces 29 and 30, a non-magnetizable rim 34 which is U-shaped in cross-section and provides a circumferential channel in which a portion of the armature winding 35 is supported. The air gap existing between the pole faces is not uniform, each of the pole faces being cut back as clearly shown in Figs. 11, 12 and 13 to increase the air gap over a portion of the pole faces at one side. 40 The purpose of this arrangement will hereinafter be fully pointed out in connection with the operation of the device.

Mounted on the shaft 17 in addition to the escapement 16 and the motor armature 45 is a lantern pinion 36 which meshes with a train 36^a of suitable gearing for propelling the several hands (not shown) of the clock.

Attention is directed to the fact that 50 power is applied to the escapement shaft 17 which operates at a relatively high speed and is geared down to the slower moving hands of the clock instead of being applied to the slow moving shafts which are geared 55 up to the escapement shaft and to the faster moving hands according to usual practice. By this means a large amount of friction in the works is avoided and the clock is improved by increasing its accuracy and 60 reliability.

While other well known forms of escapements may be used, I prefer the three-legged dead-beat escapement shown in the drawings. This escapement is provided with a

plurality of triangular projections or driving teeth 37—38—39 which are secured to but are insulated from the body of the wheel; and radial arms or stopping teeth 40—41—42.

The fork 20 is pivotally mounted at its 70 upper end by means of a pivot pin 43 and has an enlargement 44 at its lower end which is apertured to form shoulders 45—46. A driving pallet 47 is secured to and is insulated from the shoulder 45 while a driving 75 pallet 48 is secured to and is in electrical contact with the shoulder 46. The location of the fork 20 with reference to the escapement wheel 16 is such that the driving teeth 37—38—39 extend into the aperture 49 of 80 the fork and are adapted to engage the driving pallets 46 and 47 as hereinafter explained, the escapement shaft 17 extending freely through the aperture of the fork.

The fork 20 is also provided with stopping pallets 50—51 which are laterally opposite each other and are adapted to cooperate with the stopping teeth of the escapement wheel as hereinafter explained.

As clearly shown in Fig. 7 the magnetizable armature disk 33 is provided with notches so that the armature has the form of a wheel with three arms 54, 55 and 56 and the channel-shaped non-magnetizable rim 34. The disk armature is wound with three 95 coils 57—58—59, each of which extends diametrically across the disk and adjacent to opposite edges of two of the arms which have the form of sectors. Each coil comprises a plurality of turns but has the general form of a semi-circle since the wires only extend across one of the side faces of the disk, the remainder of the coil being disposed in the channel-shaped rim of the armature. By reference to Fig. 1 it is 100 therefore evident that only that portion of the coil which is adjacent to the flat surface of the disk is influenced by the magnetic lines of force constituting the field existing between the pole pieces 29—30 of 110 the field magnet.

As clearly shown in the diagrammatic view of Fig. 14, one terminal of each of the coils 57—58—59 is connected to the armature disk itself. The other terminal of 115 each is insulated from the disk and from the shaft but is connected to one of the driving teeth of the escapement wheel which, as already pointed out, are insulated from the escapement disk and are electrically independent of each other. The arrangement of parts is obviously such that when one of the driving teeth 37—38—39 engages the pallet 48, a circuit will be established with 120 one of the coils of the armature.

Before describing the other modifications of my invention I will set forth the operation of the one already described. Assum-

ing that the parts occupy the positions shown in Fig. 3, that the driving tooth 39 has just finished giving an impulse to the pallet 47, driving the fork 20 and the pendulum 19 to the right, and that the motion of the escapement wheel has been stopped by the tooth 40 engaging the pallet 51: the pendulum will now complete its swing to the right and its direction of motion will reverse. After it has returned to the position shown in Fig. 3 and has moved a little farther to the left, the tooth 40 will clear the pallet 51 and the escapement wheel will be free to turn.

When the escapement wheel is in the position shown in Fig. 3, the armature disk 33 is in the position relative to the pole pieces of the magnet as shown in Figs. 2 and 11. The magnet winding 28 is energized but there is no current in any of the armature coils. Under these conditions the magnetic field existing between the pole faces attracts the adjacent sectors of the armature disk tending to draw them into the air gap. Inasmuch as the air gap is greater at the right where the pole faces are cut back than at the left, the magnetic field is more powerful at the left and consequently the disk armature is moved to the right, or, in other words, in a clockwise direction (counter-clockwise direction as viewed in Fig. 2). This movement of the disk armature produces, of course, a corresponding rotation of the escapement wheel (in a clockwise direction as viewed in Fig. 3), and the driving tooth 38 engages pallet 48, thereby giving the lever and the pendulum an impulse to the left. This impulse is produced by the magnetic action of the magnet upon the armature independently of the armature coils.

The rotation of the disk armature and of the escapement will continue until the tooth 42 engages the stop pallet 50 the relative positions of the field magnet and armature of the motor being as shown in Fig. 12. The disk tends to move still farther in the same direction by reason of the same magnetic action but is prevented at this time from doing so by the pallet 50. The pendulum now continues its swing to the left and on its return stroke the escapement wheel is again released. When released it turns a little farther in a clockwise direction by the magnetic impulse as above indicated and the driving tooth 39 engages pallet 48. The field and armature are now as shown in Fig. 13. Immediately, when contact is made, one of the coils of the armature is energized and by reason of the current transversing the coil a new impulse is imparted to the disk in the same direction giving the pendulum an impulse to the right and bringing all the parts into the positions

in which they are shown in Fig. 3, except that another driving tooth has taken the position occupied by the tooth 39. The cycle is repeated as long as current is supplied to the motor.

It is evident that if the armature coil were not energized there would be no tendency for the armature to move in the same direction after the first impulse, but the coil is designed and wound so that when it is energized the influence of the magnetic field upon it is stronger than the influence of the field upon the adjacent magnetizable arm of the armature and is exerted so as to impart another impulse in the same direction, to the armature.

The circuit connections may be traced with reference to Fig. 14 as follows: An electric circuit is permanently established from a battery 90 which represents any suitable source of energy to field magnet winding 28 through a conductor 91, circuit being completed through conductor 92 to the opposite terminal of the battery. When one of the driving teeth of the escapement, as for example the tooth 38 engages the driving pallet 48 a motor circuit is temporarily completed from the conductor 91, through a branch 93, bearing sleeve 22, shaft 17, armature disk 33, armature coil 59, conductor 94, tooth 38, pallet 48, fork 20 and pivot pin 43 which is connected to the frame 23 and to conductor 92. The coils are so wound and formed that only a single radial section of each coil is influenced by the field of force at one time and by suitably connecting the coils, the direction of the resulting motion is always clockwise.

By slightly modifying the actuating lever 20 as shown in Fig. 6, by adding thereto a light resilient contact member 60, the apparatus may be made self-starting. The resilient contact is substantially U-shaped and is attached to the lever within the aperture 49 and extends just into the path of travel of the driving teeth 37-38-39 and in such position that whenever the clock is stopped and the pendulum and lever come to rest in a central position one of the driving teeth will engage the spring and thereby be in position to complete a circuit through one of the armature coils as soon as energy is supplied to the receiving circuit of the clock. This feature is particularly valuable for large clocks or such as are located with their works in a relatively inaccessible position or with their axis secured to a rigid base so that the pendulum cannot readily be started by hand or by tilting the whole clock.

Another modification of my invention is shown in Figs. 8, 9 and 10 to which reference may now be had.

For particularly accurate time keeping, it is desirable to insure that a uniform im-

pulse be imparted to the balance wheel or pendulum so that less reliance is placed on the isochronism of these parts. By making each impulse equal to every other impulse the amplitude of every oscillation is the same and consequently the oscillations will be made in more nearly equal periods of time.

In the embodiment of my invention disclosed in Figs. 1 to 7 inclusive, the impulses imparted to the pendulum were alternately dependent upon magnetic attraction, and an electro-dynamic expulsion. The impulses exerted by the electro-magnetic attractions are inherently more accurately uniform and regular than are the impulses which are dependent, not only on the strength of the magnetic field but also upon the form and location of the armature coils and the current traversing one of the coils at any given instant. I have accordingly in the modification of my invention which I will describe in detail hereinafter, utilized only the electro-magnetic attractive impulses for transmitting the motion to the pendulum and have utilized the electro-dynamic impulses merely for the purpose of moving the disk armature into a position for the next magnetic impulse to be effected. With this arrangement it is therefore obvious that the pendulum will always receive an impulse in the same direction instead of being propelled alternately in opposite directions; in other words, the pendulum receives an impulse once in each complete cycle instead of twice in each complete cycle of its movement. In order to avoid, to an even greater extent the possibilities of error, a permanent magnet may be utilized instead of the electro-magnet shown in the drawings for producing the motor field.

This arrangement secures the advantages of the gravity or remontoire escapement, generally used in astronomical clocks as well as those pertaining to the semi-independent escapement commonly used in marine and other chronometers.

Corresponding parts are designated by the same reference characters as those employed in the previous figures. The bearing sleeves 21 and 22 are not in this case insulated from the stationary supporting plates 23 and 24 and the coils of the disk armature instead of being connected to the driving teeth 37-38-39 of the escapement are respectively connected to a plurality of projecting pins 61-62-63 which are insulated from and extend laterally from a disk 64 and are successively engaged by a relatively stationary yielding contact finger 65 (see Figs. 10 and 15). The disk 64 is secured to the shaft 17 adjacent to the disk armature or at some other convenient point, and in fact the pins can be mounted on the arma-

ture itself if desired. The pins correspond in number and location to the driving teeth of the escapement. The pendulum actuating lever 20^a, as shown in Fig. 9, has only a single driving pallet 47* which is not insulated from the lever and receives a driving impulse once for each complete cycle of movement of the lever. The energization of the armature coils is effected by the successive contacting of the pins 61-62-63 with the stationary contact 65.

The operation of this structure is similar to the structure of the previous figures except that the electrodynamic impulse which is imparted to the escapement wheel in the same manner, produces a free movement of the escapement wheel instead of a driving movement. The free movement is such as to bring the next sector of the disk armature into position to be attracted by the field magnet.

Still another modification of my invention is shown in Figs. 16 and 17 of the drawings.

Referring to these figures the structure here shown comprises a disk armature which is similar to the disk 33 of the motor already described. It has no armature winding and consequently the non-magnetizable rim is superfluous. Instead of a single field magnet, it is provided with a permanent magnet 70 having pole pieces 71 and 72, and an electromagnet 73 which is located on the opposite side of the disk axis and has pole pieces 74 and 75. Each pair of pole pieces corresponds in form to the pole pieces 29 and 30 of the motor 18.

The winding 76 of the electro-magnet, instead of being constantly energized is controlled by a circuit closer and is periodically energized.

The circuit closer may be comprised of the escapement wheel driving teeth, coöperating with one of the driving pallets of the pendulum lever, or a separate circuit closer, as for example the circuit closer 78, may be provided. This device is similar to the circuit closer 64 of the previous figures and need not be described again in detail.

The operation of this motor is as follows: Assuming that the electro-magnet is de-energized, the permanent magnet produces a 60 degree advancement of the escapement wheel. This stroke draws one of the iron segments of the disk armature into the air gap of the permanent magnet. In this position, the circuit closer completes a circuit through the coil of the electro-magnet and thereby another forward movement of the armature is produced, the electro-magnet being arranged to exert sufficient force to overpower the permanent magnet. The action of the escapement wheel in imparting impulses to the pendulum is the same as hereinbefore described.

The permanent magnet may be replaced by a second electro-magnet which may then be energized in alternation with the first, but I prefer to use the permanent magnet 5 and utilize its impulses for driving the pendulum or balance wheel of the clock for the sake of uniformity of action.

The electro-magnets may be made to operate with a high degree of accuracy by designing the magnetic circuit to operate over 10 the knee of the saturation curve where variations in the magnetizing currents have a very small effect upon the magnetic field.

The lower end of the fork 20^a may be entirely cut away in the form shown in Fig. 9 15 if desired, as only a single driving pallet is used.

It is evident that various structural modifications may be effected within the spirit 20 and scope of my invention and I intend that only such limitations be imposed as are indicated in the appended claims.

What I claim is:

1. An electrically propelled clock comprising an isochronous vibrator, an escapement, a driving shaft therefor, and an electric driving motor connected to directly act 25 upon said shaft.

2. A clock comprising an escapement, a 30 driving shaft therefor and a motor having an armature directly attached to said shaft arranged to impart a succession of rotative impulses to the shaft.

3. A clock comprising a pendulum, an escapement, a driving shaft therefor and an electric motor arranged to impart a succession 35 of rotative impulses to the shaft, and means for controlling the periodicity of the motor impulses.

4. A clock comprising a pendulum, an escapement, a driving shaft therefor and an electric motor arranged to impart a succession 40 of rotative impulses to the shaft, and means dependent upon the escapement for controlling the periodicity of the motor impulses.

5. A clock comprising a pendulum, an escapement, a driving shaft therefor, and an electric motor adapted to impart a succession 45 of rotative impulses to the shaft and comprising a field magnet, a disk armature, armature coils therefor, and means dependent upon the escapement for controlling energization of the coils.

6. A clock comprising a pendulum, a 50 pendulum fork, an escapement having a plurality of electrically independent driving teeth, a driving shaft for the escapement, an electric motor mounted on the shaft, and coils 55 for the motor adapted to be successively energized in response to the co-operative action of the escapement and the pendulum fork.

7. A clock comprising a pendulum, a pendulum fork having driving pallets, a source

of electric energy connected to one of the 65 driving pallets, an escapement comprising a plurality of electrically independent driving teeth, a driving shaft for the escapement, an electric motor mounted on the shaft and having a plurality of armature coils respectively connected to the driving teeth 70 of the escapement, the opposite terminals of said coils being connected to the source of electric energy.

8. A clock comprising a pendulum, a pen- 75

dulum fork having driving pallets, a source of electric energy connected to one of the driving pallets, an escapement comprising a plurality of electrically independent driving teeth, a driving shaft for the escapement, an electric motor comprising a field magnet adapted to produce a constant magnetic field, a disk armature mounted on the shaft and arranged to cut the magnetic field, a plurality of coils extending diametrically 80 across one face of the disk armature, a non-magnetizable circumferential support in which the remainders of the coils are mounted, said coils being electrically connected at one end to the said source of energy and at 85 their opposite ends to the respective driving teeth of the escapement, whereby the coils are successively energized as the driving teeth make contact with the electrically active driving pallet.

9. An electrically propelled clock comprising an escapement and a rotary motor adapted to operate at substantially the speed 90 of the escapement and connected to drive said escapement.

10. A clock comprising an escapement, a driving shaft therefor and an electric motor arranged to impart a succession of rotative impulses to the shaft, and means dependent upon the escapement for controlling 100 the periodicity of the motor impulses.

11. A clock comprising an escapement, a driving shaft therefor, and an electric motor adapted to impart a succession of rotative impulses to the shaft and comprising 105 a field magnet, a disk armature, armature coils therefor, and means dependent upon the escapement for controlling energization of the coils.

12. A clock comprising an escapement, a driving shaft therefor, an electric motor comprising means tending to exert a succession of rotative impulses to the shaft alternating in direction, and means for counteracting alternate impulses whereby a succession 115 of uni-directional impulses are imparted to the shaft.

13. A clock comprising an escapement, a driving shaft therefor, an electric motor comprising means tending to exert a succession of rotative impulses to the shaft alternating in direction, means for counteracting alternate impulses whereby a suc- 120

125

sion of uni-directional impulses are imparted to the shaft, and means dependent upon the escapement for controlling the periodicity of the motor impulses.

- 5 14. A clock comprising an escapement, a driving shaft therefor, an electric motor comprising means tending to exert a succession of rotative impulses to the shaft alternating in direction, and electro-responsive
10 means controlled by the escapement for

counteracting alternate impulses whereby a succession of uni-directional impulses are imparted to the shaft.

In witness whereof I have hereunto set my hand in the presence of two subscribing 15 witnesses, this 3rd day of December, 1914.

EDWIN H. MESSITER.
